UNITED STATES PATENT OFFICE

167,411

TIE RACK OR THE LIKE

Bert M. Lester, New York, N. Y.

Application August 4, 1951, Serial No. 16,153

Term of patent 14 years

(Cl. D33—8)

To all whom it may concern:

Be it known that I, Bert M. Lester, a citizen of the United States of America, residing in New York, county of New York, and State of New York, have invented a new, original, and ornamental Design for a Tie Rack or the like, of which the following is a specification, reference being had to the accompanying drawing, forming part thereof.

Fig. 1 is a front perspective view of a tie rack or the like showing my new design.

Fig. 2 is a side elevational view thereof.

I claim:

The ornamental design for a tie rack or the like, substantially as shown.

BERT M. LESTER.
